UNITED STATES PATENT OFFICE.

ALVIN V. ROWE, OF GALESBURG, ILLINOIS, ASSIGNOR TO G. E. COLEY, OF MAYWOOD, ILLINOIS.

FUEL-SAVING DEVICE FOR AUTOMOBILES.

Application filed July 2, 1920. Serial No. 393,710.

To all whom it may concern:

Be it known that I, ALVIN V. ROWE, a citizen of the United States, a resident of Galesburg, in the county of Knox and State of Illinois, have invented new and useful Improvements in Fuel-Saving Devices for Automobiles, of which the following is a specification.

This invention has reference to a means 10 or mechanism for simultaneously actuating by and with the spark lever of an automobile, the valve controlling the supply of fuel, such as gasoline, or the like, to the carbureter.

15 The principal object of the invention is to provide for the saving of gas during the operation of the automobile, by connecting the spark lever and spark rod with the fuel supply valve of the carbureter; whereby, when 20 the spark lever is moved to retard the spark, additional fuel is supplied to the carbureter, and when the spark lever is moved to advance the spark, the fuel supply is lessened.

While my invention will be found applicable to different makes of automobiles, I have designed it, and it is here shown and described as applied to the spark lever, spark rod and carbureter of a "Ford" automobile. The "Ford" car is provided with a forked 30 rod having connection with a T bar which controls the needle valve used to regulate the supply of fuel, such as gasoline, to the carbureter. The amount of fuel consumed may be regulated if the driver would operate this forked rod after the engine was warmed up, but very few, if any drivers pay attention to this phase of their driving, more particularly because this forked rod is located on the right hand side of and under 35 the dash of the car where it is very difficult to get at, and further, because very few drivers realize the importance or saving which may be effected by the use of this forked rod. With the use of my attachment, connecting as it does the T bar of the carbureter with the spark lever and spark rod, the driver, when moving the spark lever will automatically and simultaneously effect the movement of the needle valve controlling 40 the fuel supply, and operate it to increase or decrease the fuel supply and effect a considerable saving in the cost of operating his car, without the necessity of his having in mind the cost of operations, which is taken 45 care of by my attachment.

The needle valve controlling the fuel supply to the carbureter is adjusted, as will be understood, to effect a normal supply of fuel under certain weather conditions, and it is intended with the use of the forked rod mentioned, to make it possible for the driver to regulate such valve as he may see fit. My attachment does not change this condition, leaving the forked rod free to be manipulated whenever desired and without disturbing the connections of my attachment between the T bar and the spark lever and spark rod.

That the invention may be more fully understood, reference is had to the accompanying drawings, forming a part of the description, showing a preferred embodiment of the invention, in which:

Figure 1 is more or less a diagrammatic side elevation showing my invention applied to the spark lever, spark rod and carbureter of a "Ford" automobile;

Figure 2 is a plan view of the attachment shown in Figure 1;

Figure 3 is a detail in plan of the mechanism attachable direct to the T bar of the carbureter;

Figure 4 is a view similar to Figure 3, except that the forked rod has been partially turned, releasing a locking means preparatory to adjusting the fuel supply valve;

Figure 5 is a cross-section as the same would appear on the line 5-5 Figure 3, parts being shown in full lines;

Figure 6 is a detail cross-section as the same would appear if taken on the line 6-6 Figure 3, and

Figure 7 shows two different elevations of a clamp member for connecting an operating rod to the spark rod.

Like characters of reference denote corresponding parts throughout the figures.

In Figure 1 of the drawings so much of the body and hood of a "Ford" automobile is illustrated in dotted lines to illustrate the application of the invention to the spark lever, spark rod and the carbureter. The hood is designated "A", the dash "B" and the engine "C". "D" refers to the steering post having the hand steering wheel "E" 105 and extending alongside of and parallel with said post is the spark rod "F" provided with the spark lever "G", within easy reach of the operator as he grasps the hand steering wheel "E". "H" designates the carbureter 110

containing the needle valve for controlling the fuel supply thereto, such valve not being shown, but operatively connected therewith is the stem "I" having thereon the 5 cross-head "J". The last two elements constituting, what is known as the **T** bar. This **T** bar is provided with the spaced diametrically disposed openings *j* to receive the legs *k* of the forked rod "K", which passes up 10 through the dash into the inside of the automobile body and having the crooked end *k'* to be grasped by the driver when he desires to turn the forked rod "K" to operate the **T** bar to open or close the needle valve, not 15 shown, and regulate the supply of fuel to the carburetor. All the foregoing parts are well known and their functions well understood by drivers of "Ford" automobiles, and by those versed in the art of automobile 20 constructions, and their uses need not be further elaborated on here.

My attachment includes a plate or disk 1, having the spaced diametrically disposed openings 2 to receive bolts 3 which pass 25 through the openings *j* in the **T** bar and engageable by nuts 4. Said bolts and nuts secure the plate or disk to the **T** bar. This plate or disk 1 is further provided with an arc shaped slot 5 and with an opening 6. 30 Said slot 5 and last mentioned opening are diametrically disposed and at right angles to the disposition of the openings 2 in the said plate or disk. Instead of the legs *k* of the rod "K" being inserted through the openings *j* in the head of the **T** bar, they enter 35 through the slot 5 and the opening 6, and through this connection when the driver wishes to adjust the needle valve, not shown, through the **T** bar, he merely turns the 40 forked rod "K" in the direction desired.

The plate or disk 1 is rotatably carried by an annular toothed ring 7, by locating the plate or disk 1 in the ring between two or more lugs 8, and the internally disposed 45 annular toothed ring 9, see Figures 3 and 5. As will more fully appear, the plate or disk 1 may be turned with the ring 7 or turned by the forked rod "F" independently of said ring.

Connected with the plate or disk 1 is a spring rod 10. Looking at Figures 3 and 4, one end of said spring rod is connected at 11 to the plate or disk 1, preferably by welding and crossing the slot 5; its opposite end 55 passes through a guide 12 and enters between the teeth of the toothed ring 9. Co-incident with the slot 5 the rod 10 is formed with a coil 13. One of the legs *k* of the forked rod "K" passes through the coil 13 60 and the other leg *k* of said rod "K" passes through the opening 6 in the plate or disk 1 alongside of the spring rod 10 so that the latter may bear thereagainst, see Figures 3 and 4.

When the forked rod "K" is turned, its

leg *k* in the slot 5 moves to the end of said slot which will release the free end of the spring rod 10, as shown in Figure 4, when the plate or disk 1 and the **T** bar may be given rotational movement to adjust the needle valve, not shown, controlling the fuel supply to the carburetor. When the forked rod "K" is released, the end of the spring rod 10 re-enters a tooth of the toothed ring 9. The spring rod 10 when in the position 75 shown in Figure 4, in a tooth of the toothed ring 9 locks the ring 7 and the plate or disk 1 so that the ring and plate or disk may be actuated together from the spark rod "F" in manner, as I shall now explain.

The ring 7 is formed or provided with an extension 14 with which may be detachably connected the rod 15 which passes between the cylinders of the engine to the other side of the hood where it is coupled to a clamp 16 secured to the spark rod "F". It will thus be observed that when the driver oscillates the spark lever "G" and the spark rod "F", a crosswise reciprocal movement is imparted to the rod 15 which will impart rotational movement to the ring 7, the plate or disk 1, and also to the **T** bar which will open or partially open, or close or partially close the needle valve, not shown, controlling the fuel supply to the carburetor.

To apply my attachment to the automobile, the forked rod "K" is detached from the **T** bar and my plate or disk 1 and ring 7 bolted thereto in the manner shown in Figure 6, when the forked rod "K" is then connected to the plate or disk 1, as already explained. The clamp 16 attached to the spark rod F and the rod 15 coupled to the clamp 16 and the ring 7, the attachment is then in place for use.

In the operation of the device, when the spark lever G is moved to retard the spark, the ring 7 and plate or disk 1 are rotated in a direction to supply more fuel to the carburetor, and when the spark lever "G" is moved to advance the spark, the ring 7 and plate or disk 1 are rotated in a direction to shut down the supply of fuel.

With the use of my device, it is obvious that the advancing of the spark compels the driver to shut off the gas. It will be seen, therefore, that when the engine is running along twenty to thirty miles an hour, the driver may advance his spark, and at the same time, run the automobile on a less supply of fuel. When climbing a hill, it is presumed that the spark lever is moved to retard the spark, and at the same time that the retarding takes place, more fuel is given and therefore increasing the power for the purpose of climbing the hill.

It is a well known fact that power is needed to climb a hill, and the reason that the spark is retarded, is because the engine runs less revolutions per minute, thus re-

quiring the spark to be retarded. When running on level ground, the engine is speeded up and the driver can therefore advance the spark, and at the same time, cut down the supply of fuel, resulting in a great saving of the fuel, all of which it is believed will be understood without further explanation of the uses of the device.

What I claim is:—

10. 1. In a fuel saving device for automobiles, in combination, an attachment comprising a plurality of rotatable members, means for connecting said attachment to the fuel control valve of the carbureter, means for imparting rotational movement to one of said members independent of the other members, and means releasably connecting the members together for operating said attachment as an entity by and simultaneously with the spark lever.

20. 2. An attachment for the carbureter of an automobile, comprising an annular ring, a plate rotatably held in said ring, means for connecting said plate to said carbureter, means for rotating the plate independently of the ring, and means to operate the ring and plate in unison.

30. 3. An attachment for the carbureter of an automobile, comprising an annular ring having an internally arranged toothed ring, a plate rotatably held in said annular ring, means on the plate movable into and out of engagement with said toothed ring, means for connecting said plate to said carbureter, and means to operate the attachment as an entity.

35. 4. An attachment for the carbureter of an automobile, comprising a plate attached

to the carbureter to adjust the same, a spark control member, a second carbureter adjusting member operably connected to the spark control member, means releasably connecting the plate and the second carbureter adjusting member for movement in unison, and means for operating the plate and simultaneously releasing the second carbureter adjusting member from the plate.

40. 5. An attachment for the carbureter of an automobile, comprising a plate attached to the carbureter for adjusting the same, a second carbureter adjusting member movable relatively to the plate and connectible to the carbureter through the plate, means having a play connection with the plate to operate the same, and means releasably locking the plate and the second carbureter adjusting member for movement in unison, said locking means being rendered inoperative by said plate operating means during its play movement.

45. 6. An attachment for the carbureter of an automobile, comprising a plate attached to the carbureter for adjusting the same, a second carbureter adjusting member movable relatively to the plate and connectible to the carbureter through the plate, means having a play connection with the plate to operate the same, and a locking detent carried by the plate and releasably connecting the latter to the second carbureter adjusting member, said detent being rendered inoperative by and during movement of the plate operating means.

50. In witness whereof, I have hereunto affixed my hand this 19th day of June, 1920.

ALVIN V. ROWE.
